ELECTRIC COFFEE PERCOLATOR OR OTHER SIMILAR ARTICLE

Norbert Delacroix, Lyons, France

Application February 4, 1948, Serial No. 144,268

Term of patent 7 years

(Cl. D44—26)

To all whom it may concern:

Be it known that I, Norbert Delacroix, a citizen of the French Republic, residing at Lyons (Rhône), France, and having my post office address at 11 Rue du Commandant Faurax, Lyons (Rhône), France, temporarily residing at Hotel Martinique, New York, N. Y., United States of America, have invented a new, original, and ornamental Design for an Electric Coffee Percolator or other Similar Article, of which the following is a specification, reference being had to the accompanying drawings forming part thereof.

Figure 1 is a top plan view and Figure 2 is a front elevational view of an electric coffee percolator showing my new design:

The dominant features of the design reside in the parts drawn in full lines as shown.

I claim:

The ornamental design for an electric coffee percolator or other similar article, as shown and described.

N. DELACROIX.
